A. A. YOUNG.
BRUSH STOCK AND HANDLE.

No. 74,027.

Patented Feb. 4, 1868.

Fig. 2.

Attest,

J. L. Newton
S. F. Leambut

Inventor

Albert A. Young

United States Patent Office.

ALBERT A. YOUNG, OF BOSTON, MASSACHUSETTS, ASSIGNOR TO HIMSELF
AND GEORGE T. DALTON, OF SAME PLACE.

Letters Patent No. 74,027, dated February 4, 1868; antedated January 16, 1868.

IMPROVED BRUSH-STOCK AND HANDLE.

The Schedule referred to in these Letters Patent and making part of the same.

TO ALL WHOM IT MAY CONCERN:

Be it known that I, ALBERT A. YOUNG, of Boston, in the county of Suffolk, and State of Massachusetts, have invented a new and useful Improvement in Brushes; and I hereby declare that the following is a full and exact description thereof, reference being had to the accompanying drawings, and to the letters of reference marked thereon, making a part of this specification, of which—

Figure 1 represents a longitudinal section of the invention.

Figure 2, a transverse section of the same.

The letter A represents the body of the brush, B the cap or cover, C the handle, D the screw, *a* the groove, *b* the pin or bottom of handle.

My invention consists in providing an extension-handle to a brush or duster, in such a manner that the handle may be used at either end of the brush, as the wear of the same may require. And in order that others may understand the nature and use of my invention, and be enabled to manufacture the same, I will proceed to explain it.

I apply or put in the bristles, or other dusting-material, into the wood or body part of the brush, of whatever material made, in the usual mode of making brushes. In the upper part or top of the wood or body of the brush, I make a channel or groove, either entirely within the body or partially within, and cover the remaining part with tin, or any suitable material, nailed or fastened to the same. In this channel or groove I place a handle, running the entire length of the body of the brush, and extending at one end in length sufficient for a handle, to use in any desirable manner. The handle is free to slip either way, but that it may be firm, I insert a screw or other fastening at either or both ends of the body of the brush, passing down through the handle into the body again, when the screw is taken out, that the handle may not be pushed entirely out, and also that it may not roll or turn in the hand. I have made a slight groove under the groove for the handle, and put a pin to steady the handle. When one end of the brush becomes worn, and it is necessary or economical to wear the other end, I have only to withdraw the screw and push in the handle, and the other end of the extended handle becomes a handle for use, as before. Instead of one extended handle, I may divide the handle so that either part may be pushed in or drawn out, as needed, putting a ring at the end of the handle.

I am aware that there are other devices for the same purpose, but I claim that my device is novel, cheap, and of practical utility.

What I claim as my invention, and desire to secure by Letters Patent, is—

The combination and arrangement of the body of the brush with respect to the cap B, the handle C, the screw D, the groove *a*, and the pin *b*, whereby the handle C may be extended at either end of the brush, the several parts being constructed and arranged with respect to each other substantially in the manner and for the purpose set forth.

ALBERT A. YOUNG.
